WARNING SIGNAL FOR CROWNING
MACHINES

James E. Anglo, St. Paul, Minn., assignor to Coca-Cola Bottling Company of Minnesota, Incorporated, Minneapolis, Minn., a corporation of Minnesota

Application December 28, 1946, Serial No. 719,096

9 Claims. (Cl. 116—67).

1
This invention relates to warning or signal apparatus adapted to be associated with automatic or semi-automatic machinery wherein a line of articles are moved in some phase of the operation in abutment and adapted to warn an attendant or operator when there is a break in the line of moving articles.

While applicable to a number of automatic or semi-automatic machines in a production or supply line, my invention has particular adaptability to commercial crowning and bottling systems for carbonated or other beverages.

It is an object of my invention to provide a simple, inexpensive but nevertheless highly efficient signal apparatus adapted to be readily attached or to be constructed as standard equipment in machines such as bottling and crowning machines for beverages and having the function of immediately giving a warning signal when a break occurs in a moving line of articles such as crowns through temporary lack of supply or improper feeding of the articles in their line of travel.

More specifically, it is an object to provide in warning apparatus of the class described, a source of air supply under pressure with means for directing the same against the abutting articles in line of travel and having combined therewith and at the other side of said line of articles, a signal device responsive to said discharge of air only when a break occurs in said line of abutting articles.

In bottling apparatus which usually includes dispensing or bottle-filling mechanism with automatic crowning mechanism, the crowns or caps move continuously and at high speed in abutting, side-by-side relationship through a chute and are fed thereby progressively and at high speed to the bottle crowning mechanism which applies the crown successively and clinches the same upon the filled bottles. Crown selector mechanism selects the crowns from a hopper and delivers at high speed, the crowns successively to the upper end of said chute. Sometimes, temporary clogging occurs in the selector mechanism or a delay in crown feeding to the chute occurs, occasioning, if not immediately detected, many bottles to pass through the apparatus without being crowned and, consequently, expensive hand labor in pulling the bottles from the line and returning them to the crown mechanism and loss of merchandise and production efficiency.

With my improved apparatus, immediately upon a break in the line of crowns being fed to the crowning mechanism, through the chute, a

2
warning signal is given enabling the attendant or operator to immediately start the line of crowns in proper abutting relation.

These and other objects and advantages of my invention will be more apparent from the following description made in connection with the accompanying drawings, wherein like reference characters refer to similar parts throughout the several views and in which:

10 Fig. 1 is a front perspective view showing a typical bottle-crowning machine with my signal apparatus attached thereto;

Fig. 2 is a side perspective view of the same;

15 Fig. 3 is a side elevation view showing the crown chute with the side face thereof cut away and also showing the signal device of the warning apparatus in detail; and

20 Fig. 4 is a top section view taken substantially on the line 4—4 of Fig. 3 showing the signal device of the warning apparatus.

Machines are in widespread use today which perform a productive operation on a multiplicity of articles moving in a supply line substantially abutting one another. An example of such a **25** machine is a bottle-crowning machine, such as the one illustrated which is used in soft drink bottling plants, breweries and the like. These crowning machines have a hopper 6 which is adapted to hold a supply of crowns 7. Crown selector mechanism, including a rotary vane-equipped disc 6a is associated with hopper 6 to individually select the crowns and carry them to the outside of the hopper and drop the same in vertical position for feeding rapidly and successively, the crowns to the upper end of a supply chute 8. Said crown chute 8 has one end fixed to the lower, diminished portion of the hopper 6 and chute 8 is disposed downwardly therefrom and curved inwardly at the bottom portion to **30** successively feed the crowns 7 onto a crown platform 9 disposed beneath a crowning head 10.

The machine shown has twelve crowning mechanisms, each including a crown platform 9 and a crowning head 10, as shown in Fig. 1. These **35** crowning mechanisms revolve so that said chute 8 feeds crowns 7 onto successive crown platforms 9. The outward face of the crown chute 8 is slotted so that the crowns 7 are partially visible as they pass downward. The lower curved portion of said chute 8 also has its outer face slotted.

40 A source of filtered air under pressure is provided and supply line 11 has one end connected with said source and the other end connected to a master valve 12. A tube 13 runs from said valve up to the bottom of said hopper. Signal tube 14

is connected in said line 13 and runs up to the top of the slot in the curved portion of said chute 8 where it terminates in nozzle 15. Signal valve 16 is provided to control the flow of air in signal tube 14. An elongated transverse slot 17 is cut in the rear, inward face of said chute 8 directly opposed to nozzle 15. A signal device, such as a whistle 18 is mounted with an air-receiving element such as its mouthpiece abutting the portion of the rear inward wall of said chute 8 surrounding the elongated slot 17.

Supply line 11 conducts the compressed air up to valve 12, and when said valve is open, the air flows into tube 13. Said tube 13 directs the air against the crowns 7 at the bottom of hopper 6, to prevent clogging of the crowns 7 as they enter chute 8. The crowns 7 flow downwardly in substantial abutment, one against the other. With signal valve 16 open, the air passes into signal tube 14 and flows out through nozzle 15 and is thereby directed against the line of crowns which are interposed between said nozzle 15 and the mouth of whistle 18 mounted around slot 17. It will be seen that as long as there is a constant flow of crowns 7 downward in chute 8, the compressed air stream from nozzle 15 will not impinge upon the mouth of whistle 18, but as soon as this stream is interrupted indicating a clogging of the crowns in the hopper or lack of supply thereof, the air will enter the mouth of said whistle and said whistle will give an alarm. An attendant may then quickly unclog the crown selector mechanism or see that the hopper is supplied with crowns as the case may be, or if an adjustment requiring some time is necessary, the machine may be shut off until the adjustment may be made.

With further reference to the air discharge nozzle 15 it will be noted that this nozzle is directed diagonally downwardly to assist rather than impede the normal progression of crowns or other articles down the feeding chute. Thus, an additional and important function is obtained through my apparatus in aiding and accelerating the force of gravity in the progressive feeding of the articles in abutting relationship.

The air supply for my discharge nozzle 15 as well as the crown dislodging jet 13a at the upper end of tube 13 may be derived from any suitable source. Several conventional types of bottling machines have a source of air supply connected therewith which is utilized as illustrated in the accompanying drawings, at present to assist and accelerate the progressive discharge of crowns from the lower curved end 8a of the feeding chute. To this end, a tangential connection by a fitting 20 with the lower end of chute 8a is made, the discharged air being projected against the edges of the respective crowns as they approach the end of the chute and positively forcing said crowns into the socket of the crowning mechanism.

From the foregoing description, it will be seen that I have provided a simple, highly efficient and economical signalling apparatus adapted to be readily installed in conventional automatic and semi-automatic machinery such as crowners and bottlers and capable of utilization in other machinery where a line of articles progressively move in substantial abutment.

It will of course, be understood that various changes may be made in the form, details, arrangement and proportions of the parts without departing from the scope of my invention.

What I claim is:

1. A signal apparatus to give a warning when a break occurs in a line of articles moving in a machine in substantial abutment, comprising a nozzle-forming element adapted to be connected with a source of air supply under pressure, means for directing said nozzle-forming element against one side of the articles in travel and a signal device adapted to be mounted at the opposite side 10 of the line of articles and opposed to said nozzle-forming element and responsive to the discharge therefrom to give a warning signal when no articles are interposed between said nozzle-forming element and said signal device.
- 15 2. The structure set forth in claim 1 wherein said signal device comprises a whistle with its intake element or mouth disposed in opposition to said nozzle-forming element.
- 20 3. Signal apparatus adapted to give a warning when a break occurs in a line of articles moving in a machine in substantial abutment, a nozzle-forming element adapted to be connected with a source of air supply under pressure, means for directing said nozzle-forming element at an acute 25 angle converging with the direction of travel of said articles and against one side of the line of articles and a signal device having an air-receiving signal element mounted at the opposite side of said line of articles in opposed relation 30 to said nozzle-forming element, said signal device being responsive to the discharge of air to give a warning signal when no articles are interposed between said nozzle-forming element and said signal element.
- 35 4. A signal apparatus for bottle crowning machines adapted to give a warning when a break occurs in the moving line of abutted crowns being progressively fed, to the crowning mechanism, comprising a nozzle-forming element 40 adapted to be connected with a source of air pressure, means for directing said nozzle-forming element against one side of the line of crowns and an air-responsive signalling device having an air receiving element disposed at the opposite side 45 of said moving line of crowns in opposition to said nozzle-forming element whereby a warning signal will be given whenever the space between said nozzle element and said receiving element is unobstructed.
- 50 5. The structure set forth in claim 4 wherein said nozzle-forming element directing means maintains said nozzle element at an angle converging with the line of travel of said crowns to assist rather than restrict the travel of said 55 crowns.
6. In combination with a machine adapted to perform a productive operation on a multiplicity of articles in travel, said articles moving in a line in substantial abutment, a warning apparatus 60 comprising a source of fluid supplied under pressure, a nozzle connected with said source and directed against one side of the abutting articles in travel, a signal device mounted at the opposite side of the line of articles and opposed to said 65 nozzle and responsive to the discharge of fluid therefrom to give a warning signal when there are no articles interposed between said nozzle and said signal device.
7. A warning apparatus adapted to give an 70 alarm of a break in a line of articles moving in abutment, comprising a source of air supply under pressure, an air line connected with said air supply source, a nozzle connected with said source and directed against the abutting articles 75 in travel, a sounding device disposed behind said

air supply source in opposed relation to said nozzle and responsive for operation to the discharge of air from said nozzle when the space between said nozzle and said sounding device is unobstructed.

8. In combination with a bottle crowning machine and a mechanism that discharges the 10 crowns into a chute leading to a pressure-applying element, a warning apparatus comprising a source of air supplied under pressure, a jet connected to said air source, said jet directing a flow of air against a line of crowns moving in substantial abutment in said chute, a signal device mounted in spaced relation opposing said jet, said abutting crowns being interposed between said jet and said signal device, said signal being responsive for operation to the discharge of air from said jet when the space between said jet and said signal device is unobstructed.

9. In combination with a bottling crowning machine having a crown delivery chute with a slot or opening in the outer face thereof to expose one side of a line of crowns in travel, a sounding device mounted in fixed relation on the inner side of said chute and having an entrance 25 extending through the opposite side of said chute, a source of air supplied under pressure, a jet

connected to said air source and directed against a line of crowns moving in substantial abutment in said chute and disposed in directly opposed spaced relation to the entrance of said sounding device, whereby said crowns are interposed between said jet and said device, and whereby an audible signal will be given when a break in the line of crowns occurs in said chute between said jet and said entrance of the sounding device.
